UNITED STATES PATENT OFFICE.

GEORGE SCOTT CHILES, OF CHICAGO, ILLINOIS.

RAILWAY TRUCK.

Application filed May 15, 1922. Serial No. 561,132.

To all whom it may concern:

Be it known that I, GEORGE SCOTT CHILES, a citizen of the United States, and a resident of Chicago, in the county of Cook and State of Illinois, have invented certain new and useful Improvements in Railway Trucks, of which the following is a specification.

The invention claimed herein relates to forms of construction especially though not exclusively designed for use in applying the invention described and claimed in my Patent No. 1,457,345, granted June 5, 1923. The application of the principles of the invention described and claimed in that patent necessitate certain changes in constructional forms heretofore used. The forms described herein are adapted to that purpose, but before proceeding to the description thereof I will state generally the purpose and nature of the invention in connection with which these forms of construction find their principal utility. The purpose of that invention is to improve the distribution of the springs, particularly by widening the spring support of the bolster to resist the tendency of the bolster to tilt, and distributing the springs over a longer base of support longitudinally of the side-frame in order to avoid too great concentration of the load at the central part of the side-frame. A further purpose is to accomplish this result while retaining the entire spring assemblage between the columns of the side-frame, and at the same time to provide space for a larger number of springs than hitherto commonly used, and to effect this purpose without lengthening the side-frame and wheel base. I have been enabled to accomplish these results by the use of the arrangement of the springs described herein in combination with the forms of side-frame and bolster described herein and in my copending applications Serial No. 470,465, filed May 17, 1921, and Serial No. 516,554, filed November 21, 1921, and in my Patent No. 1,457,345. While certain features of my improved spring assemblage, bolster, spring plank and side-frame may be used independently; in the preferred forms of my invention they are all related and cooperate to the accomplishment of the purpose above described.

Figure 1 is a side elevation of a side frame, one end being broken away, showing

the springs, bolster and rollers between the bolster and spring cap, all constructed to cooperate in effecting the purposes above stated.

Figure 2 is a plan view from beneath of the structure shown in Figure 1.

Figure 3 is a sectional view on the line 17-17 of Figure 1.

Figure 4 is a section on the line 18-18 of Figure 1.

Figure 5 is an end elevation of the bolster and spring cap shown in Figure 1 omitting the rollers.

Figure 6 is a sectional view on the line 19-19 of Figure 1.

Figure 7 is a fragmentary view showing a modification of the spring cap and cooperating part of the side-frame.

Figure 8 is a section on line 21-21 of Figure 7.

Figure 9 is a side elevation partly in section of another form of side-frame, bolster and spring assemblage.

Figure 10 is a bottom view of the structure shown in Figure 9.

Figure 11 is a section with parts removed on line 29-29 of Figure 9.

Figures 12 and 13 are sections on the lines 30-30 and 31-31 of Figure 9.

Figure 14 is a top view of the end of the spring plank shown in Figure 9, and

Figure 15 is a side elevation of the same.

Figure 16 is a longitudinal sectional view of the end of a built-up bolster constructed to cooperate with my improved spring assemblage.

Figures 17 and 18 are sectional views on lines 40-40 and 41-41 of Figure 16.

Figures 19 and 20 are side elevations of the end and central part respectively, of a bolster of the type known as the Simplex, but embodying new features adapting it to my invention.

Figure 21 is a view from beneath of the structure shown in Figure 19.

Figure 22 is an end view of the bolster shown in Figures 19 to 21, the upper part of the springs being shown in place.

Figures 23, 24 and 25 are an end view, section and bottom view respectively of a modified form of end casting adapted to be used in place of the end casting shown in Figures 19 to 22, and having provision for rollers between the spring cap and bolster.

Figures 26, 27 and 28 are a top, side and end view respectively of the end of a bolster of built-up construction and embodying means for accommodating my improved 6 spring assemblage.

Figures 29, 30 and 31 are views similar to Figures 26, 27 and 28 respectively showing another form of built-up bolster.

In structures heretofore designed, and 10 some of them used to a limited extent, attempts have been made to increase the number of springs supporting the bolster. In some instances this object has been attained by widening the spring group transversely 15 of the side-frame, and in other instances the additional springs have been introduced by lengthening the spring group longitudinally 20 of the side-frame. The widening of the spring group transversely of the side-frame 25 involves several objectionable features. To accommodate such a widened group, the part of the side-frame constituting the seat for the springs has to be widened to an extent that produces an objectionable overhang. 30 The widening of the group has the further effect of increasing the length of that part of the end of the bolster which must be limited in depth to make room for the springs. Ordinarily the depth of the bolster 35 is increased immediately inside of the springs in order to provide the necessary strength, and it is desirable to carry the deep part of the bolster as far toward the ends as possible. Widening the spring group also 40 has the effect of disposing some of the springs at an increased distance from the longitudinal center of the side-frame, which has the effect of throwing the resultant 45 spring load farther from the longitudinal center of the side-frame whenever, due to 50 differences in level between the track rails, the bolster tends to assume an inclined position. Attempts to increase the number of springs by increasing the length 55 of the spring assemblage longitudinally 55 of the side-frame involved either increasing the distance between the columns, or the placing of some of the springs outside 60 of the columns. In those instances where 65 side-frames have been designed to accommodate an increased number of springs between the columns, it has been found necessary to 70 greatly increase the amount of metal in the side-frame in order to provide sufficient 75 strength for the increased length of the part of the side-frame upon which the springs 80 rest between the columns. Furthermore, such lengthened spring assemblages heretofore proposed have interfered with the brake 85 beam, and have therefore necessitated 90 lengthening the side-frame and wheel base 95 in order to obviate interference between the spring plank and side-frame with the brake beam. In structures heretofore proposed 100 wherein the increased number of springs has

been provided for by placing additional springs outside of the columns, it has, of course, been necessary to provide the bolster with some form of separable end member 105 extending around the columns for the purpose of coacting with the end springs. This introduces an additional element of cost, and is objectionable in practice in that it adds 110 complexity to the structure. Furthermore, when the additional springs are placed outside of the columns, the length of the spring group longitudinally of the side-frame may be increased to such an extent as to render 115 the use of some equalizing means necessary in order to avoid torsion upon the bolster 120 when all four wheels are not in the same plane.

In order to obviate the objections above 125 pointed out, I have devised a spring assemblage wherein I increase the length of the spring assemblage longitudinally of the side-frame without either substantially increasing the transverse width of the side-frame and its spring seat, or introducing any 130 other element to interfere with the brake beams. With my improved spring assemblage, I find it possible, without interference with the brake beam, to use six springs with a shorter wheel base than that now used for the accommodation of five springs. I effect 135 this result by using a central group of 140 springs which may occupy the same space heretofore utilized for the commonly used four and five spring groups, and place the 145 added springs one at each end of the central 150 group, and upon or adjacent to the longitudinal center line of the side-frame. By 155 this means, I accommodate the added springs 160 without departing substantially from the 165 limits of width now observed in the construction of side-frames.

In order to arrange the springs as above 170 described with the entire spring assemblage, including the single end springs between the columns, I have provided an improved 175 side-frame construction whereby I am enabled to locate all of the increased number of springs between the columns not only without increasing the weight of the side-frame, but actually lightening it. I have effected 180 this purpose by constructing the tension member of the side-frame with its center of mass lying from end to end substantially in a suspension line curve. By this 185 means, substantially all of the stresses due 190 to the vertical load in the lower or tension member, are thrown into tension. In side-frames as heretofore constructed, the central part of the lower or tension member 195 upon which the springs are seated has been 200 calculated as a beam, in addition to its function as a member of the side-frame truss. It is for this reason that spreading the 205 columns of such side-frames for the accommodation of an additional number of 210

springs has necessitated a great increase in the amount of metal used, such additional metal being necessary to provide strength for this part when calculated as a beam. By 5 utilizing the suspension line as the basis for the form of the tension member with the result of throwing the stresses due to vertical load in tension, I have been enabled to increase the separation of the columns without 10 involving the necessity of using extra metal to provide the necessary strength. If it be attempted to design a side-frame to accommodate a spring assemblage of increased length longitudinally of the side-frame, difficulty is encountered especially in the forms 15 of side-frames heretofore in use in providing vertical space for the accommodation of the outermost springs of the group between the bolster and lower member of the 20 side-frame, this difficulty being due to the upward inclination of the tension member towards the end of the side-frame. The lengthened spring assemblage and suspension line curve which I have adopted for the 25 tension member when calculated for the vertical load to which the side-frame is subjected, is of such a form as to provide greater vertical clearance for the end springs of the group. The lengthening of the spring 30 assemblage longitudinally of the side-frame flattens the suspension line, and thus increases the vertical space necessary for the end springs of the assemblage. Owing to the lengthening of the spring assemblage 35 and the differences in distribution of the springs, I have found it necessary in those forms of my invention in which a spring plank is used, to devise a modified form of spring plank.

The adoption of the suspension line form of tension member and the resultant throwing of the stresses into tension, gives greater latitude in adapting the cross-sectional form of the tension member to the accommodation 40 of the springs and bolster than is possible when the tension member is subjected to severe bending stresses. The bending stresses to which types of side-frames now in use are subjected necessitate a relatively 45 great vertical cross-sectional depth in the tension member, which depth, taken in connection with the necessary road clearance, imposes a limitation upon the depth of the bolster opening, and consequently upon the 50 depth of the bolster end. With the tension member in the form of a suspension line and the stresses substantially all in tension, the vertical depth of the tension member may be much less than in the forms of construction now in use, and the height of the bolster opening may be correspondingly increased. The necessary tensile strength in 55 the tension member is preserved by increasing its width transversely of the side-frame, 60 the increased width affording space for

proper seating of the springs without the extent of overhang necessary in the present form of side-frames. The transverse widening of the tension member also serves the purpose of increasing the resistance offered to transverse and twisting forces imposed upon the frame in service. The increased vertical height of the bolster opening also admits of constructing the bolster end of greater vertical depth, thereby securing the necessary strength with less metal. The saving in weight in both side-frame and bolster increases with the increase in the capacity of the cars.

In Figures 1 to 8, I have illustrated my 65 invention in connection with an integral side-frame and a spring cap between the springs and bolster. In all of these views except 5, lateral motion rollers, ordinarily known as Barber rollers, are shown between 70 the bolster and spring cap. Referring to Figure 1, I have shown a side-frame comprising an upper compression member 28 and lower tension member 29 which come together and form the projecting end 30 below which the journal box is designed to be attached, as usual. The tension member 29 is so formed that the center of mass throughout its length lies substantially in a 75 suspension line curve, the suspension line being calculated from the vertical load for which the truck is designed. As appears in Figure 2, the end springs 31, 32 extend into recesses formed in the spring plank at 46, 46, thus shortening the spring assemblage. By the use of the single end springs 31, 32, which are characteristic of all of my spring arrangements, the suspension line is preserved at the points 33, 34 by seating 80 the end springs below the upper edges of the side walls of the tension member as illustrated. That is, opposite the seats of the end springs the side walls of the tension member extend above the spring seats thus elevating the cross sectional center of 85 mass at these points.

The lower part of the tension member from 35 to 36 is a box section, the upper wall being formed by the spring seat 37, and the lower wall being provided with 90 two lightener openings 38. The side walls are provided with an outwardly projecting flange 39. The spring seat 37 effects a junction at 35 with the upwardly extending lower web 40 of the tension member. From 95 point 41 upwardly the tension member takes the form of a U-section open on the upper side. As appears in Figure 1, the central part of the spring seat 37 is at a lower elevation than the end parts, the spring 100 seat being stepped upwardly at 42. The flange 41 at the upper edges of the side walls, however, follows the curve shown, the abrupt upward deflection being confined to the spring seat which extends be- 105

tween the side walls. The elevated ends of the spring seat 37 serve to keep the cross-sectional center of mass of the tension member substantially in the suspension line curve at this point, and this same result is contributed to by the fact that the side walls and upper edge flange of the tension member rise to and above the spring seat at the points 41. In the embodiment of my invention illustrated in Figure 1, I have shown a spring plank 43 riveted to the upper wall of the tension member, and have also shown a block 44 covering the rivet heads, and in this instance serving also to raise the central group of four springs to the same level as the end springs 31, 32.

The spring plank embodied in this form of my invention is provided with side flanges 45. As shown most clearly in Figure 2, the edges of the spring plank are inwardly curved at 46, and the side flanges 45 follow the same outline, the side flanges projecting upwardly a short distance between the end springs and the central group of springs, as indicated at 47 (Figure 1). The narrowing of the spring plank at 46—46 makes it possible to shorten the spring assemblage by an amount equal to the difference between the full width of the spring plank and its narrowed width at 46—46.

In Figures 1, 2, 3, 4 and 6, I have shown lateral motion rollers 48 between the spring cap 49 and the bolster 50. The columns 51 are provided with wear faces 52 which resist forces acting transversely of the bolster. The central opening between the columns 51 is widened immediately below the wear faces 52 to an extent sufficient to receive a spring cap 49, which is wider than the bolster and of sufficient width to overlie the entire spring assemblage. The spring cap 49 serves to bring the end springs 31, 32 into cooperation with the bolster 50. As clearly shown in Figure 4, the under side of the bolster 50 is provided with concave surfaces 53 extending transversely across its under surface, and opposed to corresponding concave surfaces 54 upon the upper side of the spring cap 49. Rollers 48 lie between these concave surfaces. End forces acting upon the bolster are resisted in part by the upward movement of the bolster incident to its movement upon the rollers. The bolster is otherwise free to move freely through the opening in the side-frame except for the limitation imposed by the stops 55 upon the sides of the bolster, which stops are so located as not to come into play except upon extreme movement of the bolster relative to the side-frame. As appears clearly in Figures 1 and 6, the spring cap 49 is provided with flanges 56 which overlap the front and rear faces of the columns 51. The spring cap 49 is thus

effectually held against horizontal movement transversely of the side-frame. The cap, however, is free to move vertically upon the wear faces 57 at the sides of the widened part of the central opening immediately below the wear faces 52. Immediately below the wear faces 57 the central opening in the side-frame is still further widened as indicated at 58, the widening at this lower portion being sufficient to permit clearance for the flanges 56 of the spring cap in order that it may be inserted in and removed from the side-frame.

In Figure 5, I have shown a detail of the end of the bolster 50', together with a spring cap 49', and the upper parts of the springs. The construction illustrated in this view is similar to that shown in Figures 1 to 4 and 6, except for the omission of the lateral motion rollers between the spring cap and bolster. In this construction, the bolster is provided with flanges 59 which restrain it against endwise movement relative to the spring cap. The construction shown in the detail views of Figures 7 and 8 is similar to that illustrated in Figures 1 to 6, except for the fact that the spring cap 49' is provided with a narrowed end which is received between flanges 60 projecting inwardly from the column 51'.

In Figures 9 to 15, I show my invention in connection with a spring grouping similar to that shown in Figure 2. In the form shown in Figure 9, the seats 85 for the end springs are elevated above the seats for the central group of springs. The portions 85 of the spring seats shown in Figure 9 form a structural part of the tension member and serve not only to support the end springs, but to contribute to the resistance of the principal stresses upon the tension member. In the form shown in Figure 9, the spring seats 85 are continued outwardly, and with the other walls of the tension member, form a box section for a short distance. The spring plank 86 embodied in this form extends beneath the central group of springs only and is recessed opposite the end springs to permit shortening the spring assemblage as above described. The construction of the tension member embodied in this form illustrates another method of keeping the cross-sectional center of mass of the tension member in a suspension line curve, while at the same time accommodating my improved spring assemblage. The bolster shown in Figure 9 is provided with seats for the end springs at a higher level than the central part which rests upon the intermediate springs, these differences in level conforming to the different elevations at which the springs are supported on the tension member.

In Figures 16 to 18, I have shown a bol-

ster end conforming generally to the type of construction known as the "Simplex," but with a channel 105 substituted for the plate used in the Simplex construction, and with an end casting 106 adapted to cooperate with the Simplex bolster construction, and designed to also cooperate with my improved spring assemblage and spring plank. The bolster casting 106 is provided with 5 projections 111 designed to rest upon the end springs of my improved spring assemblage. A spring assemblage similar to that shown in Figure 9 or other spring assemblages, may be used with the bolster end shown in Figures 16 to 18. I have substituted the channel 105 for the plate member used in the Simplex construction in order to increase the transverse strength of the bolster. As shown in Figures 16 and 17, 10 the side flanges 107 of the tension member channel are folded down near the ends, as indicated at 108. The end casting 106 is secured to the bolster by means of rivets 110, similar to the present Simplex construction.

In Figures 19 to 22, I show a bolster end casting of a form adapted to cooperate with my improved spring assemblage applied to a bolster otherwise constructed as the Simplex bolsters are now made. The bottom view, Figure 21, and the end view, Figure 22, show the form of my improved end casting, and the disposition of my improved spring assemblage cooperating therewith. 20 The end casting shown in these views is secured to the bolster proper by means of rivets 112 in accordance with the present practice.

In Figures 23 to 25 I have shown a modification of the bolster end casting illustrated in Figures 19 to 22, the modification being adapted to receive the lateral motion rollers commonly known as the Barber rollers. In Figure 25 I have shown the bolster provided with stops 113 adapted to be received within vertical guide grooves 114 in the inner faces of the columns 115. The stops 113 have a large clearance on each side and are not designed to contact with the walls of 25 the guide groove 114 except upon extreme movement from the normal position. The spring cap 116 shown in Figure 24 is designed to be provided with guides, not shown, adapted to coact with the columns to normally restrain the bolster against any endwise movement except such as takes place upon the rollers 117.

In Figures 26 to 28 inclusive, I show the end portion of a pressed steel bolster of a type now in use, the bolster illustrated differing only from the form now in use in its adaptation to cooperate with my improved spring assemblage. The side projections necessary for cooperation with the 30 end springs 118, consist of the ends 119, of

an end casting which is secured to the end of the main body of the bolster by means of rivets 120.

The construction shown in Figures 29 to 31 is similar to that shown in Figures 26 to 28, except in the following particulars. The end casting shown in Figures 29 to 31 takes the form of a box which slips over the end of the bolster, and the projecting sides 121 of the end casting are of less vertical depth than the bolster and the central part of the casting, thereby providing higher seats beneath the bolster for the end springs than for the central group of springs. As clearly appears in Figure 29, the side walls of the bolster 122 are brought closer together at 124 at the end of the bolster in order to afford clearance for the end springs 123.

I claim as my invention:

1. In a structure of the class described, a side-frame, a spring plank supported on said side-frame, an assemblage of springs comprising intermediate springs resting on said spring plank and end springs resting on said side-frame outside of said spring plank, the intermediate springs adjacent to said end springs being offset from the straight line between the centers of said end springs, said spring plank being recessed opposite said end springs and said end springs extending into the recesses so formed.

2. In a structure of the class described, a side-frame, a spring plank supported on said side-frame, an assemblage of springs comprising intermediate springs resting on said spring plank and end springs resting on said side-frame outside of said spring plank, the intermediate springs adjacent to said end springs being offset from the straight line between the centers of said end springs, said spring plank being recessed opposite said end springs and said end springs extending into the recesses so formed, the central part of said tension member upon which said spring plank rests being at a lower level than the adjacent parts upon which said end springs rest.

3. In a structure of the class described, a side-frame having an upper compression member, a lower tension member and columns, the upper surface of said tension member between said columns forming a spring seat having end sections at a higher level than the intermediate section, said end sections having projections extending into said intermediate section, a spring plank supported on said intermediate section and provided with recesses to receive said projections, an assemblage of springs comprising intermediate springs resting on said spring plank and end springs resting on said frame outside of said spring plank and extending over and resting on said projections.

4. In a railway car truck, side-frames each comprising upper compression and lower tension members, a spring plank resting upon the central part of said tension members and connecting said side-frames, an assemblage of springs, a spring cap and bolster, said assemblage of springs resting in part upon said spring plank and in part upon said tension member outside of said 5
10 spring plank, said spring cap overlying said assemblage of springs, and rollers between said spring cap and bolster.
5. In a railway car truck, side-frames each comprising an upper compression member and a lower tension member, the upper surface of the central part of said tension member forming a spring seat having an intermediate section at a lower level than the adjoining end sections, said end 15
- sections having projections extending into 20 said intermediate section, a spring plank of substantially the width of and resting on said intermediate section of said spring seat, said spring plank having recesses into 25 which said projections on the end sections of said spring seat extend, and a bolster having a central section overlying said spring plank and having transverse projections overlying said end sections of said spring seat, and an assemblage of springs 30 comprising intermediate springs resting on said spring plank beneath the central section of the bolster and end springs resting on the elevated end sections of the spring seat beneath said projections on the bolster. 35

In witness whereof, I hereunto subscribe my name this 12th day of May, A. D. 1922.

GEORGE SCOTT CHILES.
